UNITED STATES PATENT OFFICE.

ROBERT KELLER, OF DETROIT, MICHIGAN.

BOTTLE-STOPPER.

No. 880 669.

Specification of Letters Patent.

Patented March 3, 1908.

Application filed May 4, 1907. Serial No. 371,789.

To all whom it may concern:

Be it known that I, ROBERT KELLER, a citizen of the United States of America, residing at Detroit, in the county of Wayne and State of Michigan, have invented certain new and useful Improvements in Bottle-Stoppers, of which the following is a specification, reference being had therein to the accompanying drawings.

10 In pouring liquids from a bottle or other receptacle having a closure provided with an outlet and air vent or air inlet, the stream is often intermittent or broken because of the resistance offered by the liquid at the inner 15 end of the air inlet to the entrance of the air which must often bubble up from a considerable depth, the result being a splashing, surging, irregular flow which it is difficult to direct and control.

20 This invention relates to a closure for a bottle or the like provided with an air duct which insures a steady delivery of the contents of the bottle from the discharge opening.

The invention consists in the matters hereinafter set forth, and more particularly pointed out in the appended claims.

Referring to the drawings, the figure is a view, partially in elevation and partially in section, of an upturned bottle provided with a closure embodying the features of the invention.

In the drawings, 1 represents a bottle or like receptacle whose mouth is provided with a closure whose body 2 seals the mouth either 35 by frictional engagement or other preferred connection with the wall of the mouth.

As herein illustrated the body is a cork stopper having a central plug 4 of glass, wood or the like, which extends up through the 40 cork and is provided with a metal cap 3, adapted to set or screw on over the openings. The closure has an outlet 10 which is a duct through the body and may have a pouring spout, lip or like directing device on the outside. An air duct 5 is likewise formed in the body, and its inner portion leads through a nipple 6 or the like on the inside of the closure. This nipple is connected to an inner tube 7 of suitable length to extend toward 45 the bottom of the bottle or receptacle, by a joint which permits angular movement of the tube 7 in all directions. This joint comprises a length 8 of rubber tubing or like flexible material not corrodible by the contents of the bottle.

At the lower end of the tube 7 a float 9 is

secured. This may be hollow, of any suitable material not attached by the liquid in which it is to be immersed, or a cork or wooden plug may be used, as herein illustrated. It is of sufficient buoyancy to float the tube and bring its lower or free end to the upper level of the liquid when the bottle or receptacle is tilted on its side for outpouring. As a consequence of this construction, the 60 inner end of the tube is always carried either nearly or quite to the top of the liquid when decanting, thus insuring quiet, unimpeded ingress for the air after the liquid in the tube has been expelled by the first intake of air. 65 This permits the liquid to escape thereafter in a quiet, unbroken stream which is readily controlled and directed. It is of value for use in ink bottles or the like, where there is special need that the outpour be regular and 70 quiet and easily directed.

Obviously, the construction may be varied, and I do not care to limit myself to any particular form or arrangement of parts.

I claim as my invention:—

1. A bottle stopper comprising an inelastic core, having a discharge duct and a vent extending longitudinally therethrough a ring of elastic material surrounding the lower portion of the core adapted to frictionally engage and seal the mouth of a bottle, a piece of flexible tubing leading from the inner end of the vent, a piece of inflexible tubing secured in the free end of the flexible tubing and a bulbous float secured on the free end of 85 the outer tube.

2. A bottle stopper having a discharge passage, and an inwardly projecting apertured nipple, in which the air passage terminates, a flexible tube connected to the nipple, a straight piece of inflexible tubing connected to the free end of the flexible tube a float on the free end of the tubing, and an imperforate metal cap having screw-threaded engagement with the outer end of the stopper body. 95

3. A bottle stopper comprising an inelastic core provided with a discharge duct and an air passage extending longitudinally therethrough having an exteriorly screw-threaded outer end and a shoulder adapted to seat itself on the rim of a bottle mouth a bushing of elastic material surrounding the reduced portion of the core adapted to frictionally engage the mouth of a bottle, an apertured nipple on the core in which the air passage terminates projecting beyond the body of 100 the stopper, an air tube connected at its 105

inner end by a short piece of flexible tubing to the nipple, an axially apertured float secured on the outer end of the air tube, and an imperforate cup closing over the outer end 5 of the core having a screw-threaded flange engaging said outer end.

4. The combination with an ink bottle, of a stopper therefor consisting of an inelastic core provided with a longitudinal discharge 10 duct and an air passage having an enlarged outer end provided with an annular shoulder adapted to seat itself on the rim of the bottle mouth, a bushing of elastic material secured concentrically on the reduced portion of the

core adapted to frictionally engage the mouth 15 of the bottle, an apertured nipple in which the air passage terminates, a piece of flexible tubing connected to the nipple, a bulbous float centrally apertured to receive and be secured on the free end of the tubing, and 20 an imperforate cap having screw-threaded engagement with the outer end of the core.

In testimony whereof I affix my signature in presence of two witnesses.

ROBERT KELLER.
